Primary Examiner — Cathron C Brooks*Assistant Examiner* — Barbara Fox*(74) Attorney, Agent, or Firm* — Barnes & Thornburg LLP(57) **CLAIM**

I claim the ornamental design for a tablet computer, as shown and described.

DESCRIPTION

FIG. 1 is a front perspective view of a tablet computer of the present invention.

FIG. 2 is a rear perspective view of the tablet computer depicted in FIG. 1.

FIG. 3 is a front view of the tablet computer depicted in FIG. 1.

FIG. 4 is a rear view of the tablet computer depicted in FIG. 1.

FIG. 5 is a top view of the tablet computer depicted in FIG. 1.

FIG. 6 is a bottom view of the tablet computer depicted in FIG. 1.

FIG. 7 is a left side view of the tablet computer depicted in FIG. 1; and,

FIG. 8 is a right side view of the tablet computer depicted in FIG. 1.

The broken lines shown in the drawings are for the purpose of illustrating unclaimed portions of the tablet computer and form no part of the claimed design.
